UNITED STATES PATENT OFFICE

HARRY B. RUDD, OF DOUGLASTON, NEW YORK

RAILROAD CONTROL CIRCUITS

Application filed June 27, 1928. Serial No. 288,584.

This invention relates to railroad control circuits, such for example as may be used in connection with automatic train controlling devices signaling apparatus, etc.

5 The objects of this invention include the provision of simple, dependable and relatively inexpensive control circuits of the class above indicated, such circuits running through the rails of the track but having a 10 source of operating current carried by the moving locomotive, car or other railroad or railway vehicle.

Further and more specific objects, features and advantages will clearly appear from the 15 detailed description given below taken in connection with the accompanying drawings which form a part of this specification and illustrate merely by way of example certain embodiments of the invention.

20 The invention consists in the novel features, circuit arrangements and combinations of devices embodied by way of example in the apparatus herein described as illustrating preferred forms of the invention, together 25 with such novel control methods as are hereinafter described.

In the drawings Fig. 1 is a circuit diagram schematically illustrating a railroad track equipped with a control circuit arrangement 30 embodying my invention; and

35 Figs. 2 and 3 respectively schematically show two embodiments of the portions of the control circuits carried by the moving railway vehicle and for operation in conjunction with circuits such as those of Fig. 1.

Referring to the drawings, the two rails of a track are indicated respectively at 10 and 11, the track being divided into blocks in a well known manner by interposing insulation at 40 the rail joints at the beginning and ending of each block as indicated at 12, 13, 14 and 15. The circuit arranged as indicated is designed to operate in conjunction with trains or other vehicles moving over the track in the direction indicated by the arrow. A pair of connection wires 16 and 17 are connected to the rails 11 and 10 respectively at points adjacent the beginning of a block. At a point along the track near the end of the previous block, 45 a pair of electromagnets at 18 and 19 are lo-

cated and are both connected across the circuit of wires 16 and 17. A pair of connection wires 20 and 22 extend from the rails 11 and 10 respectively at a point near the end of the block, the wire 22 if desired being connected in series with an adjustable resistance as at 21. A pair of electromagnets 23 and 24 may be positioned along the track and located respectively adjacent the electromagnets 18 and 19. The magnets 23 and 24 are 55 both connected across the circuit of connection wires 20 and 22.

The apparatus of Fig. 2 which is located upon the moving vehicle will now be described. A suitable source of alternating current is indicated at 25 connected in series with an electromagnet 26, similar in construction to the electromagnets 23 and 24 and designed to momentarily cooperate therewith as the vehicle moves along the track. 60 Another electromagnet 27 is mounted on the vehicle preferably in approximately the same spaced relationship to the electromagnet 26 as the relationship of electromagnets 19 and 24 and of electromagnets 18 and 23. That is, the 65 magnets 26 and 27 are preferably carried on a moving vehicle in a position in alignment with the direction of movement so that when the vehicle arrives over the magnets adjacent the track, the four poles of the electromagnets 26 and 27 will all be uniformly 70 spaced from the corresponding four poles of the electromagnets 19 and 24, or the electromagnets 18 and 23.

The electromagnet 27 may be connected in 75 series with the winding 28 of a relay having an armature 29, so that whenever the coil of electromagnet 27 is suitably energized, the relay will close a circuit through its contact 80 and a suitable source of current 31 connected to a control magnet 32. The control magnet 32 may be utilized to operate any desired well 85 known form of train control device or signaling device. The arrangement above described is particularly adapted for operation in conjunction with train controlling devices of the "run-down" type which are well known in the art. Examples of such devices are disclosed in the patents to Bower, 1,261,901 of 90

April 9, 1918 and 1,399,100 of December 6, 1921.

The operation of the above described circuits will now be explained in further detail.

5 As the electromagnet 26, energized by the source of current 25 and carried by the moving vehicle, approaches a point where its poles are opposite the poles of the stationary electromagnet 24, a current will be induced in the coil of electromagnet 24. This current will normally flow through the circuit of connection wires 20, 22, resistance 21, rails 10 and 11, connection wires 16 and 17 and through coils of electromagnets 18 and 19. However, 10 if the rails 10 and 11 should be electrically connected as when a train or car is located in the control block of these rails, then the coils of electromagnets 18 and 19 will be short circuited and will not be energized by the 15 current established in the coil of magnet 24. It is also apparent that if one or both of the rails 10 and 11 should become broken apart at any point, the coils of electromagnets 18 and 19 will fail to be energized. However, 20 whenever the rails 10 and 11 are in proper condition and free from cars and trains, the energization of the stationary electromagnet 19 will cause a current to be induced in the coil of moving magnet 27, at the moment 25 when the electromagnet 26 induces a current in the coil of electromagnet 24. The current through electromagnet 27 accordingly energizes the relay coil 28, operates the relay and thus brings about the energization of the 30 control magnet 32. If the control magnet 32 is associated with a so-called "run-down" type of train control device, the impulse as thus applied to the control magnet 32 will serve to initiate the "resetting" action of the 35 "run-down" device.

40 As the moving vehicle proceeds further along the track, the electromagnet 26 will induce the current in the coil of electromagnet 23 and in a manner similar to that above described, an impulse will be induced in the electromagnet 27 if the track in the block ahead is free and clear and in good condition. Thereupon the control magnet 32 will receive a second impulse which may be utilized to stop the "resetting" operation of the 45 "run-down" device and permit such device to initiate its "run-down" action which will persist until either the device "runs down" and applies the locomotive brakes, or until 50 the next control block in the track is reached and the device is reset in the above described manner.

55 With the above described apparatus the stationary electromagnets along the track 60 may be positioned so as to come into sufficiently close proximity of the moving electromagnets 26 and 27 to permit induction of any desired control currents, but yet the electromagnets on the moving vehicle may be located far enough above the track or to one side

of the stationary magnets so that under no normal circumstances would it be possible for the moving electromagnets to strike the stationary electromagnets. Mechanical coaction of the stationary and moving circuit devices is accordingly wholly eliminated, thus greatly reducing the possibility of excessive wear or breakage. Furthermore, the source of current may with this arrangement be carried by the moving trains or vehicles so that the 70 system may be conveniently and economically maintained. The use of the alternating current insures the induction of sufficient current in the stationary part of the circuit regardless of the speed of travel of the vehicle. 75

80 It will be understood that each succeeding block of the track may be provided with stationary magnets and circuit connections in the form above described, the stationary electromagnets being spaced at a braking distance ahead of each block. The pair of electromagnets 19, 24 may be placed ahead of the pair of magnets 18, 23, a distance equal to a predetermined percentage of the length of the block ahead, in order to insure proper 85 "resetting" of the particular type of "run-down" device used.

90 In order to insure uniformity of the operation of the relay with all of the control blocks, the resistance of the various control blocks circuits may be adjusted to uniform values by the use of the adjustable resistance 21 if desired.

Under some conditions it is feasible to operate the control magnet or magnets directly 100 from the circuit of electromagnet 27, in which cases it is unnecessary to interpose the relay.

105 The embodiment of the invention illustrated in Fig. 3 is similar to that of Fig. 2, like parts being referred to by the same reference characters. However, in Fig. 3 a source of direct current is indicated at 33 connected in series with the windings 35 of the multipole rotating armature member 34. The armature member 34 may be so positioned 110 that the ends of its poles will successively assume positions approximating the positions of the ends of the poles of electromagnet 26. Accordingly, when the armature 34 is energized by the direct current 33 and rotated at a suitable speed, either a pulsating or an alternating field can be set up (depending upon the direction of winding of the coils 35), such field corresponding in function to the field established by the electromagnet 26 above described. Armature 34 may of course be rotated either from the source of power of the moving vehicle or from the car axles, or otherwise. The arrangement in Fig. 3 may be particularly desirable for vehicles upon which a dependable source of direct current is already available.

115 While the invention has been described in detail with respect to particular preferred examples thereof which give satisfactory re-

sults, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent of the United States is:

1. A control circuit comprising a railroad track control block, electrical connections extending from the rails at one end of said block to a point along the track reached by the moving vehicle previous to said block, means at said point for cooperating with means carried by the moving vehicle to establish a current in the circuit of said connections and said rails, electrical connections extending from the rails at the other end of said block to said point, and additional means controlled by said circuit and through said last named connections and cooperating with additional means carried by the moving vehicle to operate a control circuit on the vehicle.

2. A control circuit comprising a railroad track control block, electrical connections extending from the rails at one end of said block to a point along the track reached by the moving vehicle previous to said block, means at said point for cooperating with means carried by the moving vehicle to induce a current in the circuit of said connections and said rails at the moment when the vehicle passes said point, electrical connections extending from the rails at the other end of said block to said point, and additional means controlled by said circuit and through said last named connections and cooperating with additional means carried by the moving vehicle to operate a control circuit on the vehicle.

3. A control circuit comprising a railroad track control block, electrical connections extending from the rails at one end of said block to a point along the track reached by the moving vehicle previous to said block, means at said point for cooperating with means carried by the moving vehicle to induce an undulatory current in the circuit of said connections and said rails at the moment when the vehicle passes said point, electrical connections extending from the rails at the other end of said block to said point, and additional means controlled by said undulatory current and cooperating with additional means carried by the moving vehicle to operate a control circuit on the vehicle.

4. A train control system comprising means carried by the moving vehicle for establishing a varying magnetic field, a stationary electro-magnetic means positioned at the railroad track at a point ahead of a control block to be energized by said field to establish a current

through the rails of said block, control means on the moving vehicle, and means energized by said current and positioned adjacent said point for operating said control means when the circuit through the rails is continuous and not short circuited.

5. The method of establishing railroad vehicle control circuits in a system comprising a plurality of control blocks, which comprises inducing, from a source of power carried by the vehicle while on one control block, a momentary undulatory current passing through the rails of another control block ahead of the vehicle when said last named control block is clear, and utilizing said current to inductively operate a control circuit on the vehicle.

6. The method of railroad vehicle control in a system comprising a plurality of control blocks, which comprises inducing, from a source of power carried by the vehicle while on one control block, a plurality of current impulses passing through the rails of another control block ahead of the vehicle when said last named control block is clear, and utilizing said impulses to operate a "run-down" control device on the vehicle.

7. A control circuit comprising a railroad track control block, electrical conductors connected, respectively, to the rails at or adjacent one end of said block, said conductors including an electro-magnetic device, and electrical conductors connected, respectively, to the rails at or adjacent the other end of said block, said last named conductors including an electro-magnetic device, said electro-magnetic devices being positioned beside a control block adjacent said first named control block.

8. A control circuit comprising a railroad track control block, electrical conductors connected, respectively, to the rails at or adjacent one end of said block, said conductors including an electro-magnetic device, and electrical conductors connected, respectively, to the rails at or adjacent the other end of said block, said last named conductors including an electro-magnetic device, the current for energizing one of said devices passing lengthwise first through one rail of said control block and then lengthwise through the other rail of said control block, one of said devices inductively operating a control circuit on a vehicle.

In testimony whereof I have signed my name to this specification.
